UNITED STATES PATENT OFFICE.

CHARLES EDWIN RICKEY, OF PORTSMOUTH, OHIO, ASSIGNOR TO THE EXCELSIOR SHOE COMPANY, OF PORTSMOUTH, OHIO, A CORPORATION OF OHIO.

PROTECTED SEAM FOR SHOES.

Application filed April 9, 1925. Serial No. 21,818.

My present invention involves the toe structure of shoes and relates particularly to the protection of the sole seam at the toe area.

- 5 In shoes having a stitched sole, whether welt or McKay, spherical stress on the toe of the sole causes what I have determined to be radial strains upon the individual stitches.
- 10 It has been noted that in shoe wearers a large number "take off" with the toe, or step or push from the toe tip or greater toe, as distinguished from the lateral toe drive common to the aborigine or the flat foot step 15 of the degenerate walker.

This characteristic due to the toeing out or angular tread of the foot has exerted on footwear an enormous tax and strain. As long as shoe flexations are generally fore 20 and aft stitches may come and go in some semblance of adjustment, but when the play works on plural axes, the disruptive effect is tremendous.

If the sole of a shoe is considered geometrically with reference to its sole as a plane, it will be seen that in that plane the general flexion is transverse to the longitudinal axis of the shoe.

At the toe, however, the forward end is 30 substantially circular about a spot or point generally centrally of the ball of the foot. Relative to the spot the toe strains are radial and no longer confined to simple plane-like flexations, but are spherical. The wearing 35 of the stitches at the toe is therefore most serious as they can not but yield to these strains as soon as the seam is worn through at any part, or the sole worn back to give the seam insufficient support. This calls for 40 seam protection and particularly a stayed but isolated fastening so placed as not to cut into the stitches, but to afford lateral protection.

To illustrate the problem and indicate a 45 simple solution of the same in accordance with my invention, I have shown in the accompanying drawing a characteristic case. Throughout the specification and drawings like reference characters are used to indicate 50 corresponding parts, and in the drawings:

Fig. 1 is a central vertical section of a conventional shoe toe.

Fig. 2 is a sole plan thereof.

Fig. 3 is a diagrammatic view of the sole 55 plan, and

Fig. 4 is a similar section of the radial strains.

I have indicated at U an upper having a 60 welt W and a sole S stitched as at T there-through. The stitching T may be of any type as welt or McKay, and the stitching is done in the usual manner for the type of shoe, so that there will be no needle interference with any metal fastening.

If the shoe toe be observed it will be seen to have what is really a center C which lies in a theoretical longitudinal axis L-L at the intersection of the transverse breadth line B-B and is cut by an infinite number 70 of radial stress and strain lines C-R. On each of these radial lines as the toe of the shoe is flexed, there is set up torsional and shearing strains on the individual stitches T.

In addition to this strain, there is also the actual and always increasing wear on the periphery of the toe which planes off or bevels the edges of the sole. Such wear is another attack upon the stitch line, both 80 weakening the surrounding leather as well as cutting or breaking the stitches themselves.

I therefore reinforce the toe area of the sole by preferably independent unitary stays 85 or fastenings. These are by preference metallic driven members I set after the stitches T are laid and driven into protective formation about said line and in radial reference to the toe center C.

The zone I¹ is driven just outside the stitch line so that it not only takes its share 90 of radial stress, but forms an actual metallic barrier to the edge wear. The inner zone centering on C is reinforced radially as well as on the surface, while permitting all radial flexations to remain and work on normal lines.

This reinforcing of the seam is done after 100 the sole is stitched so that there is no danger of needle breakage by contact with the metal slugs or fastenings. In driving these I use a novel horn attachment for the usual slugging machine which forms the subject matter of a separate application. This facilitates the driving of the slugs closer to the 105

seam without actually cutting into it, and makes the operation a rapid, practical step in the making of the shoe.

Various modifications in the character, form and arrangement of the seam stitches, reinforcement, etc., may be employed without departing from the spirit of my invention.

What I therefore claim and desire to secure by Letters Patent is:

1. In a shoe toe having a flexation center, a circumferential stitch line, and a metallic reinforcement area disposed on both sides of the line of stitches, the outer portion of

the reinforcement area lying between the 15 stitches and the edge of the sole, and the inner portion of the reinforcement area lying inside the stitches and extending radially of said center adjacent to said stitch line.

2. In a shoe structure, a toe part including a sole stitched thereto and a plurality of independent driven metallic fastenings arranged in one or more rows in protective and reinforced relation relative to the stitch line on both sides thereof. 25

In testimony whereof I affix my signature.

CHARLES EDWIN RICKEY.
